UNITED STATES PATENT OFFICE.

GEORGE L. PREBLE, OF LYNN, MASSACHUSETTS.

COUNTER-STIFFENER.

1,091,704.

Specification of Letters Patent. Patented Mar. 31, 1914.

Application filed May 29, 1911. Serial No. 630,255.

To all whom it may concern:

Be it known that I, GEORGE L. PREBLE, of Lynn, in the county of Essex and State of Massachusetts, have invented certain new and useful Improvements in Counter-Stiffeners, of which the following is a specification.

The present invention relates to counter stiffeners for boots and shoes, and consists 10 in a number of improvements upon the counter stiffener illustrated and described in Letters Patent Number 866,732, granted me September 24, 1907. The essential feature of the counter stiffener forming the subject 15 matter of the aforesaid patent is a thin sheet of celluloid molded to the required shape and interlocked with the fibers or strands of a sheet of reinforcing fabric. In that patent the sheet of celluloid and sheet of re- 20 inforcing fabric are of the same shape and size and their edges are coextensive. Considerable difficulty is experienced in attaching the forward edges of the counter stiffener to an insole by the row of 25 stitches which attach a welt strip. This difficulty is due to the stiffness of the celluloid.

One of the features of the present invention is the provision of flexible tabs formed 30 of the reinforcing fabric which is used in conjunction with a sheet of celluloid. The sheet of celluloid is so cut that its forward ends will not extend into the path of the needle of the sewing machine by which the welt strip is attached, but the sheet of re- 35 inforcing fabric is extended beyond the sheet of celluloid and is therefore extremely flexible and may be seated closely in the angle of the shoulder of an insole. The ends of a welt strip usually overlap the forward edges 40 of a counter stiffener about one inch, more or less, and when the counter stiffener is provided, as in the present instance, with soft flexible tabs at the point of overlapping, a joint may be made which is less 45 bulky than if the sheet of celluloid extended so far as to be overlapped by the welt strip.

Another feature of the present invention is the provision of a double blank of re- inforcing fabric which is folded so as to pro-

vide two thicknesses to inclose the sheet of 50 celluloid.

Of the accompanying drawings which illustrate the invention: Figure 1 represents a perspective view of a counter stiffener in position upon the heel portion of an insole. 55 Fig. 2 represents an inverted plan view of the molded counter stiffener, a portion of the reinforcing fabric being broken away to expose the interior structure. Fig. 3 represents a cross-sectional view of a portion of a 60 shoe in process of construction. Fig. 4 represents a plan view of the several blanks of which the counter stiffener is composed. Fig. 5 represents a counter stiffener consisting of a stiffening member inclosed between 65 two layers of reinforcing fabric before being molded.

The same reference characters indicate the same parts wherever they occur.

Referring first to Fig. 4, a blank of re- 70 inforcing material is indicated at 10. A blank of celluloid is indicated at 11, and a blank of stiffer and stronger material, such as wood fiber or leatherboard, is indicated at 12. The blank 10 is composed of textile material. Flannel and felt are found to be desirable for reinforcing material. The sheet of celluloid and the sheet 12 of relatively 75 stiff material of the outlines shown are laid upon the blank 10, which has but a single 80 thickness, in the condition shown by Fig. 4. With the several members in the relation shown, the blank 10 is folded along its longitudinal central line 13 so as to inclose the 85 members 11 and 12 between two layers of reinforcing material. The blanks are then subjected to a molding process to give the article the desired shape, as shown by Figs. 1 and 2. A suitable solvent is applied to the celluloid to render it soft and sticky so that 90 it will be interlocked with the members 10 and 12 as the result of the molding operation. If a liquid solvent is used it will be applied to the celluloid prior to the molding operation, but if heat is to be used as a 95 solvent it may be applied during the molding operation.

It will be observed that the ends of the

celluloid 11 are cut away at an angle to the inner edge thereof, as indicated at 14, 14. The purpose in cutting the celluloid to this shape is to provide soft flexible tabs 15, 15, 5 of reinforcing material 10 at the forward extremities of the counter stiffener. These tabs 15 serve to attach the counter stiffener to other parts of a shoe α when the upper and welt thereof are sewed to the insole. An 10 insole is indicated at 16, an upper is indicated at 17, and a welt strip is indicated at 18. The ends of the welt strip usually overlap the ends of the counter stiffener for a distance of one inch, more or less. When 15 the counter stiffener is assembled with the other parts of the shoe, it is interposed between the lining 19 and the upper 17, as shown by Fig. 3. The welt strip 18 is laid upon the upper and the several thicknesses 20 are united with the insole by a row of stitches, as indicated at 20. The celluloid 11 and stiffening member 12 are not directly united with the insole by the stitches 20 because of the manner in which they are cut 25 away. The tabs 15 are therefore adapted to be drawn snugly into the angle of the insole formed by the shoulder 21 and feather 22. The doubling of the reinforcing material 10 avoids loose ends of threads and provides a 30 smooth inner edge for the lip 23 which engages the heel seat of the insole. The doubling of the tabs 15 also facilitates the sewing operation. The soft tabs 15 may be readily trimmed after the sewing operation 35 has been finished.

While a more efficient counter stiffener may be produced by the use of a sheet of celluloid 11, the celluloid may be omitted from counter stiffeners for shoes of inferior 40 quality, leaving the counter stiffener having only the flexible material 10 and the relatively stiff member 12, as shown by Fig. 5. In this figure the material 10 is folded to provide two thicknesses, and the member 45 12 is inclosed between the thicknesses. The formation of the stiffening member 12 provides the soft flexible tabs 15 as previously described. This counter stiffener may be molded in the usual way and may be attached to a shoe in the manner explained 50 just as if it contained a sheet of celluloid. When the celluloid is used, the counter stiffener is preferably molded so that the celluloid will lie between the stiffening member 55 12 and the foot so as to serve as a moisture-proof barrier between the foot and the stiffening member.

While the counter stiffener in the forms illustrated has been described with particularity as to the materials used and as to the doubling of the soft fabric, I do not wish to limit myself in these particulars.

The essential feature of the invention

which I believe to be broadly new is the combination of a relatively stiff molded 65 member and the soft flexible material attached thereto in any desirable manner so as to provide doubled tabs which may be easily flexed and sewed into the between-substance of a shoe.

70 I claim:

1. A counter stiffener comprising a doubled sheet of soft flexible material, a layer of celluloid between the layers of said flexible material, and a layer of relatively 75 stiff material between said celluloid and one of the layers of said flexible material, said layer of stiff material being smaller than said layer of celluloid, said layer of celluloid being interlocked with said layers of 80 flexible material outside the margin of said stiff material, and said flexible material extending beyond said celluloid to provide flexible tabs adapted to be sewed in with the between substance of a shoe by stitches 85 which do not pass through the celluloid.

2. A counter stiffener comprising a member of stiff sheet material having a heel-seat flange, and a covering therefor consisting of a member of soft flexible sheet material, 90 said covering having a crease and two confronting layers connected by the creased part, said stiff material lying between said layers and said creased part inclosing the inner edge of said flange, said inner edge being substantially coextensive with said 95 crease around the rear portion of the flange, a substantial portion of the length of said inner edge at each end of said flange being a sufficient distance from said crease to enable a needle of an inseam sewing machine to sew the inseam stitches through both layers of said soft flexible material between said crease and the inner edge of said end portions.

3. A counter stiffener comprising a layer of relatively stiff material having a heel-seat flange, and a doubled sheet of soft flexible material, said stiff material being between the layers of said soft flexible material, and the crease of said soft flexible material inclosing the inner edge of said flange and diverging from the edge of the flange to provide soft flexible tabs between the ends of said heel-seat flange.

4. A counter stiffener comprising a doubled sheet of soft flexible material having an upper body portion and a heel-seat flange, the crease of said soft flexible material being at the inner edge of said flange, 120 and a layer of relatively stiff material having an upper body portion and a heel-seat flange at the rear and sides, said layer of relatively stiff material being between the layers of said soft flexible material, said 125 flange of relatively stiff material being

shorter than the body portion thereof and shorter than said flange of said soft flexible material. 10

5. The combination with a boot or shoe having inseam stitches for joining the upper and insole, of a counter stiffener comprising a stiffening member provided with soft flexible tabs at the forward portions thereof and

secured to said upper and insole by said stitches.

In testimony whereof I have affixed my signature, in presence of two witnesses.

GEORGE L. PREBLE.
